COMBINATION TANK AND TRAILER

Joseph E. Kachnik, 2704 McKinnie Ave.,
Fort Wayne, Ind.

Filed Nov. 21, 1963, Ser. No. 77,526

Term of patent 14 years

(Cl. D14—3)

I claim:

The ornamental design for a combination tank and trailer, as substantially shown.
